[57] CLAIM

The ornamental design for a diskette storage container, substantially as shown and described.

DESCRIPTION

FIG. 1 is a perspective view of a diskette storage container showing our new design in its closed configuration;

FIG. 2 is a perspective view thereof showing the container in its opened configuration;

FIG. 3 is a partially broken perspective view showing the base member thereof, the surfaces not shown being plain or the mirror image of the corresponding surfaces of the opposite sides;

FIG. 4 is a partially broken perspective view showing the closure member and diskette support member disposed in a separated relationship from the base member, the surfaces not shown being plain;

FIG. 5 is a perspective view showing the diskette support and carrier subassembly;

FIG. 6 is a perspective view showing the carrier member of the subassembly shown in FIG. 5;

FIG. 7 is a perspective view showing one of the separator elements shown in FIGS. 2 and 5, the rear view being the mirror image thereof; and

FIG. 8 is a cross-sectional view taken along the line 8—8 of FIG. 2.
